H. H. CHARLES

INCUBATOR

Filed Nov. 9, 1922

Patented Oct. 7, 1924.

1,510,460

UNITED STATES PATENT OFFICE.

HENRY H. CHARLES, OF MANOR TOWNSHIP, LANCASTER COUNTY, PENNSYLVANIA.

INCUBATOR.

Application filed November 9, 1922. Serial No. 599,772.

To all whom it may concern:

Be it known that I, HENRY H. CHARLES, a citizen of the United States, and a resident of Manor Township, county of Lancaster, State of Pennsylvania, have invented 5 certain new and useful Improvements in Incubators, of which the following is a specification.

This invention relates to incubators, or 10 more particularly to drawers for incubators.

The object of this invention is to provide a drawer for incubators upon which is pivoted a square tray for carrying the 15 eggs. It of course is desirable that the tray should fit neatly into the cabinet to provide space for carrying as many eggs as possible, and also to have means whereby the location of the eggs may be changed 20 from time to time; therefore a further object is to provide means whereby the square tray may be conveniently turned on said pivot without unduly shaking or disturbing the eggs.

25 The objects of this invention will be more fully understood from the following description, taken in connection with the accompanying drawing, forming a part hereof and in which similar numerals refer to similar parts throughout the several views.

Fig. 1, is a sectional view through an incubator and shows a plan view of the principal elements of my invention.

Fig. 2, is a front elevation of Fig. 1, with 35 the door 4 not shown.

Fig. 3, is a sectional view of Fig. 1, somewhat reduced in size, and taken on line 3—3. The tray and drawer are shown in light broken lines when in position for conveniently turning the tray.

40 With reference to the drawing, 5 represents the cabinet of an incubator. 6 is a main drawer which is provided with guide strips 7. A secondary drawer 8 is adapted to fit under the strips 7 and thereby prevented from tilting when the same is drawn partially out as shown in Fig. 3.

The secondary drawer 8 is provided with 45 guide strips 9, between which slides a strip 10. The egg tray 11 is carried by the strip 10 and is supported on the upper edge of the drawer 8 as shown at 12 when the complete apparatus is closed.

50 A pivot pin 14 is fixed to the strip 10 and engages with the eye 15. The eye 15 may be formed by a washer soldered to the

screen 16 which forms the bottom of the tray 11.

When the incubator is in operation the eggs are placed on the screen 16 of the 60 tray. After the eggs are hatched, the chicks move forward towards the light observed through the glass 17 in the door 4. They finally fall over the edge 18 of the tray into the nursery 19, formed by the drawer 8. 65 The rear wall of the drawer 8 is made to extend above the tray 11, as shown at 24, or sufficiently high so that the chicks cannot get back of the drawer when the same is drawn partially out of the cabinet. 70

For turning the tray 11, the drawer 8, tray 11, and strip 10 are drawn to a position as shown in light broken lines, Fig. 3. When in this position the tray 11 may be conveniently turned on the pivot pin 14. 75 The door 4 is shown in light broken lines in open position.

It is apparent that the guide strips 7 might form part of the cabinet 5 and the main drawer 6 be eliminated without affecting that feature of my invention whereby the tray 11 may be conveniently turned on the pivot pin. However the drawer 6 is generally desirable when supplying my device to fit cabinets which were not originally constructed for its adaptation. 80

Having thus described my invention what I claim and desire to secure by Letters Patent is as follows:

1. In an incubator, the combination of 90 a drawer, a strip carried by said drawer, guides fixed to said drawer and adapted to control lengthwise movement of said strip, a pivot pin fixed to said strip, and a square tray adapted to revolve on said 95 pivot pin.

2. In an incubator, the combination of a cabinet, a primary drawer in said cabinet, a secondary drawer carried by said primary drawer, strips fixed to said primary drawer and adapted to prevent said secondary drawer from tilting when partially drawn, and a door adapted to close said cabinet and inclose said drawers. 100

3. In an egg carrying device, the combination of a primary drawer, a secondary drawer carried by said primary drawer, strips fixed to said primary drawer and adapted to prevent said secondary drawer from tilting when partially drawn, and a 110 rotatable tray carried by said secondary drawer.

4. In an incubator, the combination with a cabinet having a substantially square compartment, a drawer adapted to slide in said compartment, a pivot pin carried by said drawer, a square tray adapted to slide with said drawer in said compartment, and revolve on said pivot pin, and means adapted whereby said tray with said pivot pin may be moved forward relative to said drawer and thereby permit said tray to be rotated on said pivot pin.

5. In an incubator the combination with

a cabinet, a drawer in said cabinet, a pivot pin carried by said drawer, a tray supported by the side walls of said drawer and adapted to revolve on said pivot pin, means adapted whereby said tray with said pivot pin may be moved forward relative to said drawer, and a rear wall section forming part of said drawer and extending to the top of said tray.

In testimony whereof I affix my signature.

HENRY H. CHARLES.
